UNITED STATES PATENT OFFICE

RANSOM W. DAVENPORT, OF DETROIT, MICHIGAN, ASSIGNOR TO CHICAGO PNEUMATIC TOOL COMPANY, OF NEW YORK, N. Y., A CORPORATION OF NEW JERSEY

MECHANICAL REFRIGERATOR

Application filed April 28, 1927. Serial No. 187,224.

This invention relates to refrigerating outfits adapted to the storage of perishable articles and also to the freezing of liquids in small quantities. While it has aspects of general utility it is particularly applicable to mechanically-operated self-contained outfits for household use. It has direct application to closed cycle systems utilizing lubricating refrigerants of the general type disclosed in my copending applications, Serial No. 85,580, filed February 2nd, 1926, and Serial No. 106,825, filed May 5th, 1926.

One object of the invention is to provide an improved mechanical refrigerator adapted to household use. Another object is to afford a pleasing appearance and a highly convenient, compact and sanitary structure. Still another object is to provide the utmost simplicity in feeding to and from the pump or compressor. Other objects will be apparent from the detailed description which follows:

In previously disclosed apparatus and methods for expanding a mixture of vapor and gas through a body of lubricating refrigerant to evaporate the volatile component of the latter, certain conditions adapted to increase the convenience, simplicity and effectiveness of such processes and apparatus have been set forth. For example, it is preferable to feed the gas, vapor and liquid downwardly from the condenser to the evaporator and it is also preferable to feed the concentrated lubricating refrigerant solution downwardly from the concentrating evaporator to the intake of the pump.

The present invention provides for combining the mechanical refrigerating apparatus including compressor, condenser and evaporator with a cabinet in such a manner that the evaporating member, or portions thereof, may extend both above and below the compressor-condenser unit so as to conform to the conditions set forth above. The invention further provides a compact arrangement wherein the evaporator means are so disposed that the differential temperatures at which heat is absorbed by the latter do not conflict in the ice making, cooling, and lubricant concentrating functions.

In order to illustrate the invention, one concrete embodiment thereof is shown in the accompanying drawings in which:

Fig. 1 is a vertical sectional view through a self-contained mechanical refrigerator substantially on the line 1—1 of Fig. 2 and showing the apparatus unit in end elevation;

Fig. 2 is a front elevational view of the cabinet shown in Fig. 1 with the door to the freezing chamber open;

Fig. 3 is a fragmentary rear elevational view; and

Fig. 4 is a diagrammatic illustration of the parts forming the closed cycle refrigerating system substantially in relative vertical positions.

The embodiment of the invention chosen for the purpose of illustration comprises a refrigerator cabinet A adapted for household use and providing a large refrigerating or food storage chamber B, and a small chamber C above chamber B and at the front of the cabinet. Chambers B and C have walls of heat insulating material and in the present instance are shown insulated from one another. Access to the chambers may be gained through doors b and c respectively. Rearwardly of chamber C and above chamber B is a recess D adapted to contain at least a part of the refrigerating apparatus. In the present instance the apparatus mounted in recess D comprises a unit of the general type shown in my copending application, Serial No. 104,895, filed April 27th, 1926, and comprising a base 5 on which is mounted a condenser 6, a pump or compressor 7, and an electric motor 8 for driving compressor 7 and the air cooling means for condenser 6.

Heat is extracted from chambers B and C through extended heat absorbing or evaporator means arranged to contain an evaporable liquid. In the present instance the evaporator means comprises three parts connected in series. These parts comprise a freezing element 9 disposed in chamber C, a cooling element 10 disposed in chamber B and a concentrator 11 disposed in chamber C. As is evident from Figs. 1 and 4, the parts comprising the evaporator means are disposed in vertically spaced relation with the freezing

element 9 intermediate concentrator 11 and cooling element 10. Freezing element 9 preferably takes the form of a receptacle for trays 12 for the liquid to be frozen, the receptacle having double walls forming a container of limited capacity for the refrigerant and may conform generally to the freezing element disclosed and claimed in my copending application, Serial No. 105,372, filed April 29th, 1927. 5 Cooling element 10 may take the form of a simple coil of pipe as shown in Fig. 4 or may be a thin flat container for refrigerant arranged to form at least a part of the lining of chamber B after the manner disclosed in 10 my last named copending application. By preference the upper portion of chamber C in which concentrator 11 is disposed is connected with refrigerating chamber B so that air may circulate therebetween and so that concentrator 11 may get heat from chamber B and its contents by convective currents. Such circulation of air may be accomplished by providing ducts or passages c' between the 15 ends of the freezing element 9 and the walls 20 of cabinet A (Fig. 2), these ducts being extended through the upper wall of chamber B to communicate with the latter.

The elements of the evaporator means are combined with the apparatus in recess D in 30 a manner to form a closed cycle system operating on the vapor-gas principle. Condenser 6 connects with the bottom of freezing element 9 through pipe 13 and feeding device or expansion valve 14. The top of freezing element 9 connects with the bottom of cooling element 10 by a pipe 15. The top of cooling element 10 connects with concentrator 11 by a pipe 16 whose open end is adjacent the top of evaporator 11. A pipe 17 adapted to pass 35 vapor and concentrated lubricant extends from concentrator 11 to the inlet of pump 7, which in turn discharges through pipe 18 into the top of condenser 6.

It will be evident from an inspection of Fig. 45 1, that the connections from the condenser to the evaporating means and from the evaporating means to the pump are very short and direct and that the disposition of the freezing element 9 and the concentrator 11 with reference to the apparatus disposed in recess 6, is such that the products of the condenser feed downwardly to expansion valve 14 and the products of concentrator 11 drain into the pump inlet after the manner found to be most 50 advantageous and effective in systems of this type. Inasmuch as a vapor-gas system, utilizing vaporizing means which restricts circulation of liquid therein, operates at progressively higher temperatures after the manner disclosed in my copending application Serial 55 No. 77,158, filed December 22, 1925, which characteristic is taken advantage of in working with lubricating refrigerants, it is apparent that the concentrator 11 (remote from 60 feeding device 14) operates at a much higher

temperature than freezing unit 9 which is immediately adjacent device 14. In order to prevent interference through heat exchange between elements 9 and 11 of the evaporating means, suitable provision is made for insulating these elements from one another. By preference, and as shown, freezing element 9 is entirely surrounded or enclosed by a layer of heat insulating material 19 such as cork board in addition to the insulating material 70 which forms the wall of chambers B and C. 75

From the above it will be apparent that the present invention provides a self-contained mechanical refrigerator cabinet of pleasing design, so arranged that the refrigerating chambers can be easily kept in a sanitary condition and with the apparatus parts so disposed as to insure operation with maximum efficiency while permitting convenient access for inspection and repairs. The machine unit which is disposed in recess D may be and preferably is of small light construction which can be easily lifted out of its recess for replacement or repairs, or the ends of the recess may be made removable to permit sliding it in endwise, after disconnecting the pipes connecting the same to freezing element 9 and concentrator 11. 80

While a preferred form of the invention has been herein shown and described, it is to be understood that the invention is not limited to the specific details thereof, but covers all changes, modifications and adaptations within the scope of the appended claims. 85

I claim as my invention:

1. The combination with a motor driven compressor and a condenser of an evaporator extending both above and below said compressor and condenser, a heat excluding cabinet for the evaporator, said compressor and said condenser being supported by said cabinet within a vertical projection of the latter. 100

2. In a closed cycle refrigerating system operating on the vapor-gas principle a compressor, a condenser, and an evaporator extending both above and below said compressor and condenser, said evaporator comprising a low temperature part utilized for the freezing of liquid and a higher temperature part for ordinary refrigeration, said low temperature part being above said higher temperature part. 110

3. In a closed cycle refrigerating system operating on the vapor-gas principle a compressor, a condenser, and an evaporator extending both above and below said compressor and condenser, said evaporator comprising a low temperature part utilized for the freezing of liquid and a higher temperature part for ordinary refrigeration, said low temperature part being above said higher temperature part, said condenser being connected to the lower part of said low temperature part, the top of which is in turn con- 115 120 125 130

- neeted to the bottom of said higher temperature part.
4. A closed cycle system operating on the vapor-gas principle and utilizing a lubricating refrigerant comprising a compressor, a condenser, and an evaporator, said evaporator having a freezing part, a refrigerating part, and a concentrator, said freezing part and said concentrator being disposed above 10 said refrigerating part.
5. A closed cycle system operating on the vapor-gas principle and utilizing a lubricating refrigerant comprising a compressor, a condenser and an evaporator, said evaporator having a freezing part, a refrigerating part and a concentrator, said evaporator elements being disposed in vertical spaced relation with said freezing part intermediate said concentrator and said refrigerating part.
6. A closed cycle system operating on the vapor-gas principle and utilizing a lubricating refrigerant comprising a compressor, a condenser and an evaporator, said evaporator having a freezing part, a refrigerating part and a concentrator, said evaporator elements being disposed in vertical spaced relation with said freezing part and intermediate said concentrator and said refrigerating part, said compressor and said condenser being mounted substantially on a level with said freezing part.
7. A refrigerator cabinet having a freezing chamber, a refrigerating chamber beneath said freezing chamber, refrigerating apparatus of the closed cycle type operating on the vapor-gas principle comprising a compressor, a condenser, an evaporator having parts in both said chambers, and means insulating from one another the chambers in which 35 said evaporator parts are located, said cabinet having a recess rearwardly of said freezing chamber and above said refrigerating chamber to receive said compressor and condenser.
8. A refrigerator cabinet having a freezing chamber, a refrigerating chamber beneath said freezing chamber, refrigerating apparatus of the closed cycle type operating on the vapor-gas principle and utilizing 40 a lubricating refrigerant comprising a compressor, a condenser, and an evaporator having parts disposed in said chambers and connected in series, a concentrator connected to the second part of said evaporator and sub-55 jected to the heat of the chamber in which said second part is located.
9. A refrigerator cabinet having a freezing chamber, a refrigerating chamber beneath said freezing chamber, refrigerating apparatus of the closed cycle type operating 60 on the vapor-gas principle and utilizing a lubricating refrigerant comprising a compressor, a condenser, and an evaporator having parts disposed in said chambers and connected in series, and a concentrator adja- 65
- cent said freezing chamber connected to the evaporator part in said refrigerating chamber.
10. A refrigerator cabinet having a freezing chamber, a refrigerating chamber beneath said freezing chamber, refrigerating apparatus of the closed cycle type operating on the vapor-gas principle and utilizing a lubricating refrigerant comprising a compressor, a condenser, and an evaporator having parts disposed in said chambers and connected in series, a concentrator adjacent said freezing chamber and connected to the evaporator part in said refrigerating chamber, and means insulating said concentrator from the evaporator part in said freezing chamber. 70 75 80
11. A self-contained refrigerating and ice making outfit comprising a cabinet having a large chamber for articles to be preserved, a small chamber above said large chamber, a recess rearwardly of said smaller chamber, a refrigerating element in said large chamber, a freezing element in said smaller chamber, a refrigerant container in said small chamber above said freezing element, a refrigerating apparatus in said recess including a compressor and a condenser, a connection from said condenser to said freezing element, said freezing element, refrigerating element and container being connected in series in the order named, and a connection from said container to said pump and from said pump to said condenser to provide a closed cycle system operating on the vapor-gas principle and for utilizing a lubricating refrigerant. 85 90 95 100
12. A self-contained refrigerating and ice making outfit comprising a cabinet having a large chamber for articles to be preserved, a small chamber above said large chamber for liquids to be frozen, a recess rearwardly of said smaller chamber, a refrigerating element in said large chamber, a freezing element in said smaller chamber having inclosing walls of heat insulating material and adapted to contain receptacles for liquid to be frozen, a refrigerant container in said small chamber above said freezing element, refrigerating apparatus in said recess including a compressor and condenser, a connection from said condenser to said freezing element, said freezing element, refrigerating element and container being connected in series in the order named, and a connection from said container to said pump and from said pump to said condenser to provide a closed cycle system operating on the vapor-gas principle and for utilizing a lubricating refrigerant. 105 110 115 120
13. A refrigerator cabinet having chambers of differing size, the smaller chamber being disposed above the larger, refrigerating apparatus of the closed cycle type operating on the vapor-gas principle and utilizing a lubricating refrigerant comprising a compressor, a condenser, and an evaporator 125 130

having parts disposed in both said chambers and connected in series, and a concentrator in the smaller chamber connected to the evaporator and arranged to receive heat by convection from said larger chamber.

14. A refrigerator cabinet having chambers of differing size, the larger chamber being beneath the smaller chamber, refrigerating apparatus of the closed cycle type operating on the vapor-gas principle and utilizing a lubricating refrigerant comprising a compressor, a condenser and an evaporator having parts disposed in said chambers and connected in series, a concentrator in the upper part of said smaller chamber connected to the evaporator part in said larger chamber, insulating means surrounding the evaporator part in said smaller chamber and ducts at the ends of said insulated evaporator part establishing communication between said smaller chamber and said larger chamber to permit said concentrator to receive heat from said larger chamber by convection.

Signed by me at Detroit, county of Wayne,
25 and State of Michigan, this 2d day of April,
1927.
